BOOKREST FOR BATHTUBS AND THE LIKE

Winifred E. Harris-Jones, San Francisco, Calif.

Application May 9, 1934, Serial No. 724,681

4 Claims. (Cl. 4—1)

The invention relates to improvements in book rests for bath tubs and the like and has for its primary object the provision of an improved construction of the character indicated which is convenient and efficient in use and capable of economical production.

Another object of the invention is the provision of a construction of the character indicated which may be readily adjusted to bath tubs or other articles of furniture of various sizes.

Another object of the invention is the provision of a construction of the character indicated having a rack thereon adapted to be utilized for supporting books, mirrors and the like and readily foldable into compact form.

Other objects will appear hereinafter.

The invention consists in the combinations and arrangements of parts hereinafter described and claimed.

20 The invention will be best understood by reference to the accompanying drawing forming a part of this specification, and in which

Fig. 1 is a perspective view of a construction embodying the invention and shown in position 25 of use on a bath tub of conventional form;

Fig. 2, an enlarged top plan view of the construction shown with the parts folded into compact form; and

Fig. 3, a transverse section taken substantially 30 on line 3—3 of Fig. 2.

The embodiment of the invention illustrated in the drawing comprises a supporting tray 10 preferably made of sheet metal, having longitudinal sides 11 and ends 12. The upper edges of the sides 35 11 and ends 12 are rolled to form tubular beads 13 and 14. Arranged at each end of the tray 10 is a

supporting member 15 consisting of a metal rod bent into substantially U-shape with the ends or sides thereof sliding in the beads 13, the outer 40 portions thereof being bent upwardly and covered with a rubber tube 16 as shown, thereby adapting the members 15 to serve as suitable supports for engaging the top edges of the bath tub 17 or the like. Arranged at each end of the bottom of the

45 tray 10 are three transverse slots 18 and adjacent upwardly convex ribs or ridges 19 thereby adapting the ends of the tray to support soap, sponges and the like for use for bathing purposes. Additional drain openings 20 are also provided in the central portion of the bottom of the tray to prevent the accumulation of water therein.

By this arrangement a simple and convenient supporting tray is provided which is adapted to be arranged as indicated in bath tubs or other articles of furniture of various sizes.

Arranged on the bottom of the tray at one side of the central portion thereof are two upstanding pivot lugs 21 and a rack member 22 is pivotally connected therewith as shown. The rack member 22 is formed from a metal strip or bar bent into substantially U-form and the ends thereof are pivotally connected to the lugs 21 by means of the pivot pins or rivets 23.

Associated with the rack member 22 is a brace member 24 also formed from a metal strip bent 10 into U-form, the sides of the same being pivoted at 25 to the inner sides of the sides of the rack member 22 so as to be foldable within the same, as indicated in Fig. 2. The brace member 24 is reinforced and stiffened by means of transverse 15 stiffening bars 26 arranged as shown.

By this arrangement a simple and effective foldable rack is provided for the tray 10 which may be readily adjusted as indicated in Figs. 1 and 3 to support a book, mirror or the like in convenient 20 position for use by the occupant of the bath tub and may be also readily folded into compact form in the bottom of the tray as indicated in Fig. 2. The specific form and arrangement of parts is a simple and effective one for the purpose.

While I have illustrated and described the preferred form of construction for carrying the invention into effect, this is capable of variation and modification without departing from the 30 spirit of the invention. I therefore do not wish to be limited to the precise details disclosed, but would desire to avail myself of such variations and modifications as fall within the scope of the appended claims.

35 I claim:

1. A device of the class described comprising a sheet metal supporting tray having a perforated bottom and upwardly extending sides and ends the top edges of its sides being rolled into tubular 40 guides; and a support at each end of said tray formed from a wire rod bent into substantially U-shape with the ends thereof arranged to slide in said guides.

2. A device of the class described comprising 45 a sheet metal supporting tray having a perforated bottom and upwardly extending sides and ends the top edges of its sides being rolled into tubular guides; and a support at each end of said tray formed from a wire rod bent into substantially U-shape with the ends thereof arranged to slide in said guides, the outer portions of each support being bent upwardly and covered with rubber tubing to form rests to engage the corresponding edges of a bath tub or the like.

3. A device of the class described comprising a supporting tray; two upstanding pivot lugs in said tray at one side of the central portion thereof; a rack member in the form of a bar bent into substantially U-shape with the ends thereof pivoted to said lugs; and a brace member also formed of a bar bent into substantially U-form with the ends thereof pivoted to the inner sides of the sides of said rack member adjacent the free ends thereof, said brace member being adapted and arranged to fold within said rack member, and both to fold within said tray.

4. A device of the class described, comprising a supporting tray having upstanding sides; two upstanding pivot lugs in said tray at one side of the central portion thereof; a rack member

in the form of a bar bent into substantially U-shape with the ends thereof pivoted to said lugs and of a length less than the width of said tray so as to be capable of folding downwardly onto the bottom thereof; and a brace member also formed of a bar bent into substantially U-form of slightly less width than said rack member, the ends thereof being pivoted to the inner sides of the sides of said rack member adjacent the free end thereof, said brace member being shorter than said rack member and a foldable rack arranged centrally in said tray so as to permit the folding of both within and onto the bottom of said tray.
